CLAIM

The ornamental design for a medical test kit, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a medical test kit, showing our new design;

FIG. 2 is a rear view thereof, showing a test strip comprised by the new design;

FIG. 3 is a left side view thereof;

FIG. 4 is a right side view thereof;

FIG. 5 is a top view thereof;

FIG. 6 is a bottom side view thereof;

FIG. 7 is an enlarged front view of a portion of the test kit, that portion being the test strip;

FIG. 8 is a rear view thereof;

FIG. 9 is a right side view thereof; and,

FIG. 10 is a left side view thereof.

The top and bottom of the test strip are not ornamented. The top and bottom of the enlarged portion of the test kit shown in FIGS. 7-10 are not ornamented.
